CELL FOR TREATING MATERIAL BY
IRRADIATION

Richard Mason Fraps, Tucson, Ariz.

Application September 19, 1932, Serial No. 633,791

3 Claims. (Cl. 99—2)

My invention relates to an improvement in means for irradiating substances and has for one purpose the provision of means for subjecting the substance to radiation. Another object is the provision of an improved cell or container for containing a body of material during irradiation, said container being adapted to house or accommodate the entire body of material being treated, to prevent the necessity of any outside connection or circulation of the material being treated which need be effective during treatment. Other objects will appear from time to time in the course of the specification and claims.

10 My invention is illustrated in the accompanying drawings, more or less diagrammatically, wherein—

Figure 1 is a vertical section with parts in side elevation;
 Figure 2 is a section on a larger scale of the upper portion of the cell structure;
 Figure 3 illustrates a slightly variant form of cell;
 Figure 4 illustrates a further variant form of cell; and
 25 Figure 5 is a detail.

Like parts are indicated by like symbols throughout the specification and drawings.

Referring to the drawings and first to Figures 1 and 2, A generally indicates a reflector, which 30 may be parabolic, and which is apertured at A¹ to receive an axial extension, A², having inlet and outlet passages A³ whereby a cooling medium, for example water, may be introduced.

B generally indicates a cell structure, which is effectively unitary during treatment, there being no external connection for the material being treated during treatment, and any circulation or movement of the material being treated into or out of the cell during treatment. The cell B 35 includes a flask or container, B¹, herein shown as spherical, but which may be of any suitable form, which is positioned in the container, A². It is preferably spaced from the walls of the container A² to permit the circulation thereabout of the cooling medium employed. The container B¹ is continued in the form of a neck B² with the bevelled ground joint portion B³ adapted to receive the corresponding ground portion B⁵ of the upper portion B⁴ of the cell. The upper cell 40 portion B⁴ is indicated as having a spherical enlargement B⁶ preferably positioned about the focal point of the reflector A, or adjacent or at the zone of concentration of radiation from the reflector A. The member B⁴ is further enlarged 45 at the end opposite the connection B⁵, as at B⁷,

to receive any suitable closing plug, B⁸, which may be of metal and may include the sleeve B⁹ for the rotary shaft B¹⁰ which may be actuated through the pulley B¹¹ and belt B¹² from the motor B¹³ as shown for example in Figure 1.

5 At the end of the shaft B¹⁰ is a screw or agitating device C which is positioned within an inner housing C¹ fitted as at C² within an inner aperture C³ in the plug B⁸. It is further continued as a passage C⁴ which terminates as at C⁵ 10 adjacent the bottom of the container B¹. The screw may be so pitched or rotated as to cause a circulation of material downwardly along the passage C⁴ through the container B¹, upwardly through the sleeve B² and within the portion B⁴ 15 and finally through its enlarged treatment area B⁶, the circuit being continued through the apertures C⁶ in the member C¹. C⁷ indicates any suitable supply inlet for the cell, which may be closed during treatment, and through which, if 20 desired, an inert gas may be admitted, as for example nitrogen, to prevent any oxidation of the material before, during or after treatment.

Referring to Figure 3 I illustrate a form differing somewhat from the form of Figure 1. The 25 container B¹ is indicated as of smaller size, being generally cylindrical rather than spherical, the surrounding circulation of the cooling medium being omitted. The spherical enlargement B⁶, which is preferable but not necessary, may be 30 omitted, as in Figure 3, in case the angle of incidence of the radiation is such as to prevent any substantial loss by reflection. I further illustrate, in connection with Figure 3, a lower inlet, D, for the admission of nitrogen or inert gases, which 35 may be controlled by the valve D¹ at the end of the elongated passage D². The passage D may be extended inwardly into the passage C⁴ as indicated at D³ in Figure 5.

Referring to Figure 4 I may position about the 40 enlarged portion B⁶ of the cell B⁴, an outer container or wall E to form an outer jacket having the passages or connections E¹, whereby a fluid medium may be introduced into the outer jacket 45 so formed. I may employ any suitable medium, either for filtering the incident radiation, or for cooling the material undergoing treatment, or for obtaining both effects.

It will be realized that whereas I have described and shown a practical and operative device, I 50 wish my drawings to be taken as in a broad sense illustrative and diagrammatic rather than as limiting me to my precise showing. The use and operation of my invention is as follows:

I provide a cell or container for the treatment 55

of materials by subjecting them to radiation. While I do not wish to be limited, in the use of my cell, to any particular source of radiation, I find it efficient in connection with the employment of solar radiation. As an example of such use I may indicate the activation, by solar ultra violet radiation, of ergosterol, in order to impart to it anti-rachitic characteristics. In so employing the cell I may for example employ the parabolic reflector, A, which concentrates the radiation at or about a focal point or zone of concentration of radiation. I so position my cell, in relation to the reflector, that the material in the cell is subjected to such concentrated radiation. Assuming that the reflector is employed in connection with solar radiation, it is simply positioned in the sun, any suitable means being employed, so far as necessary, to keep the reflector aligned with the sun, and the solar radiation incident upon the reflector A will be concentrated, upon the cell, for example upon the spherical area B⁶.

In the form of cell herein shown I prefer to maintain a closed circulation of the material being treated, the cell including not only means for guiding the material through the zone of concentrated radiation, but also means for containing the entire mass or volume of material undergoing treatment. Hence the container portion B¹, may be positioned out of the zone of concentration. I prefer to employ a propelling or circulating screw, C, rotated by the motor B¹³, for imparting a circulatory movement to the material undergoing treatment. In order to prevent any escape of the material I employ ground joints, as above described, the cell being formed of several different parts, the various parts being all secured together by gas-tight ground joints. It will be understood that in response to rotation of the motor B¹³ the screw C moves the liquid undergoing treatment either upwardly or downwardly through the passage C⁴, the liquid being circulated beneath the wall B⁴ and through the enlargement B⁵, through the zone of maximum concentration of radiation. When the treatment has been completed, the material having been subjected to such radiation for a predetermined period, depending upon the desired conditions or results, the cell as a whole may be removed from the reflector and the material withdrawn, and a new cell, with a complete supply of material ready for treatment, inserted in the reflector.

It being sometimes desirable to cool the material undergoing treatment, to prevent overheating, oxidation and the like, I may employ a water jacket or cooling medium about some part of the cell. As an example, I may employ the jacket shown in Figure 1, or I may employ an outer jacket as shown in Figure 4, in which last case the jacket may also serve a filtering function, being interposed between the material being treated and the incident concentrated radiation.

I may maintain an inert atmosphere in the container during treatment. I may for exam-

ple supply nitrogen either through the passage C⁶, or through the passage D. Under some circumstances, as where a steady and cheap supply of nitrogen is available, I may employ the inflowing jet of nitrogen as means for maintaining circulation of the material undergoing treatment. I indicate such a structure in Figure 5, the steady delivery of nitrogen through the jet D³, having the effect of causing an upward movement of the material through the passage C⁴, which either supplements or replaces rotation of the screw C.

I claim:

1. In a device for irradiating materials by sunlight, a concentrating reflector and a cell adapted to contain the material to be treated, said cell including a portion positioned in the zone of maximum concentration of radiation of said reflector, and a storage portion positioned out of said zone extending through an aperture in the reflector together with two passages connecting said portions of the cell to provide for continuous circulation of fluid material therethrough, and mechanical means mounted within the cell adapted for forcibly maintaining such circulation.

2. In a device for irradiating materials by sunlight a concentrating reflector of relatively large area, a relatively small, approximately spherical treating chamber located substantially at the focus of said reflector, the wall of said chamber being pervious to the desired portion of the radiation concentrated thereon, a storage chamber for fluid to be treated located adjacent the reflector but outside the zone of maximum concentration of radiation, an inner wall within the treating chamber spaced from the outer wall to confine the fluid to a relatively slight depth as measured from the outer wall, a port leading from such space through the inner wall, a passage leading from within said inner wall to the storage chamber and a return passage leading from the storage chamber to the space between the said walls constituting a closed circuit for the circulation of fluid to be treated, and a rotary pumping element mounted within said inner wall adjacent its said port for forcibly moving the liquid through said circuit, together with driving means for said element extending outside the treating chamber.

3. In a device for irradiating materials by sunlight, a concentrating reflector and a treating chamber of approximately spherical form fixedly supported by the reflector substantially at the focus thereof, and a storage chamber for fluid to be treated also fixedly supported on the reflector but out of the zone of maximum concentration of radiation, together with passages connecting said chambers and constituting a closed circuit for circulation of said fluid, and mechanical means within the treating chamber operable for inducing such circulation of the fluid and provided with an operating member exposed outside said chamber.

RICHARD MASON FRAPS.
